(57) **CLAIM**

We claim the ornamental design for a cooling pack for a vest, as shown and described.

DESCRIPTION

FIG. 1 is a perspective of our cooling pack for a vest.

FIG. 2 is a front elevation view thereof.

FIG. 3 is a back elevation view thereof.

FIG. 4 is a top plan view thereof.

FIG. 5 is a bottom plan view thereof; and,

FIG. 6 is a side elevation view thereof.

The broken lines on the tab portions represent the portions of the design that form no part of the claim.
